US00D996967S

(12) **United States Design Patent** (10) **Patent No.:** **US D996,967 S**
(45) **Date of Patent:** **** Aug. 29, 2023**

(54) **CLOSURE**

(71) Applicant: **Closure Systems International Inc.**,
Indianapolis, IN (US)

(72) Inventor: **Aravind Murali**, Zionsville, IN (US)

(73) Assignee: **Closure Systems International Inc.**,
Indianapolis, IN (US)

(**) Term: **15 Years**

(21) Appl. No.: **29/788,405**

(22) Filed: **May 17, 2021**

(51) LOC (14) Cl. **09-07**

(52) U.S. Cl.

USPC **D9/453; D9/454**

(58) **Field of Classification Search**

USPC D7/392.1, 396.2; D9/440, 443, 447, 449,
D9/452-454, 499, 434-436, 452-456;
D25/62

CPC B65D 41/34; B65D 41/0457;
B65D 41/3428; B65D 55/16

See application file for complete search history.

(57) **CLAIM**

The ornamental design for a closure, as shown and described.

DESCRIPTION

FIG. 1 is a top perspective view of a closure, showing our new design.

FIG. 2 is a front view of the closure of FIG. 1, in which the opposing side views and the back views are identical.

FIG. 3 is a bottom perspective view of the closure of FIG. 1.

FIG. 4 is a top view of the closure of FIG. 1; and,

FIG. 5 is a bottom view of the closure of FIG. 1.

The broken lines are shown for the purpose of illustrating parts of the article that form no part of the claim.

1 Claim, 5 Drawing Sheets
